EDWARD W. NEWELL, OF PITTSBURGH, PENNSYLVANIA, ASSIGNOR TO THE WESTINGHOUSE AIR BRAKE COMPANY, OF WILMERDING, PENNSYLVANIA, A CORPORATION OF PENNSYLVANIA.

FRICITION DRAFT-GEAR.

1,219,579.

Specification of Letters Patent. Patented Mar. 20, 1917.

Application filed August 17, 1915. Serial No. 45,877.

To all whom it may concern:

Be it known that I, EDWARD W. NEWELL, a citizen of the United States, residing at Pittsburgh, in the county of Allegheny and 5 State of Pennsylvania, have invented new and useful Improvements in Friction Draft-Gears, of which the following is a specification.

This invention relates to friction draft gears, and more particularly as applied to railway cars for absorbing and dissipating shocks due to buffing and draft stresses.

As the space available for the installation of a draft gear is often limited, it is highly 15 desirable to provide a draft gear which can be installed in as confined a space as possible.

The principal object of my invention is to provide a draft gear of the above character and for this purpose the parts which serve 20 as follower plates are arranged at an intermediate point in the draft gear. By this means, the follower stops can be located at an interior point on the stop castings, thus permitting the use of shorter stop castings, 25 and since the usual followers are dispensed with, outside space is not required for the followers, as in the former constructions.

Other objects and advantages will appear in the following more detailed description 30 of the invention.

In the accompanying drawing; Figure 1 is a vertical longitudinal section of a draft gear mechanism embodying my invention; Fig. 2 a horizontal section thereof, as applied between the car center sills and showing the stop castings; Fig. 3 an end view of the front plunger wedge; Fig. 4 a side view thereof; Fig. 5 an end view of the rear plunger wedge; Fig. 6 a side view thereof; 40 Fig. 7 an end view of the front friction element; and Fig. 8 a central vertical section thereof.

The usual yoke 1 connected to draw-bar 2 may be provided and within the yoke there 45 is mounted a casing 3 having at the rear end, interior oppositely inclined friction faces 4.

Within the casing 3 is a draft spring 5 bearing at one end against the front end wall of the casing and at the opposite end 50 against a friction element 6 having oppositely inclined friction faces 7. Centrally of the draft gear there is provided opposing plunger wedges 8 and 9, each having oppositely inclined friction faces and wedge 55 blocks 10 having friction faces are mounted

so that the friction faces thereof engage corresponding friction faces of the plunger wedges 8 and 9, the friction element 6, and the casing 3.

A rod 11 extends through a central opening in the friction element 6 and engages the front plunger wedge 8 at the rear end and at the front end the rod engages a plate 12 which bears against the draw-bar 2.

The rear plunger wedge 9 is provided with 65 a stem 13 which engages a bearing plate 14 in the yoke 1.

The front plunger wedge 8 is provided with lateral extensions 15 which are adapted to engage stops 16 of the stop castings 17 70 secured to the car center sills 18 and the rear plunger wedge 9 is provided with similar extensions 19 adapted to engage stops 20 of said stop castings.

In order to provide initial compression 75 in the draft spring, the spring may be made of such length that when the parts are assembled, the wedge blocks will be at their innermost positions with the plunger wedges pressed apart.

When the draft gear is to be applied to the car, a chisel is driven into one of the recesses 21 provided at the rear end of the casing 3, so as to engage the rear face of the plunger wedge 9. Said wedge is thus forced forwardly, and the wedge blocks 10 are then moved outwardly and forwardly, causing the front friction element 6 to also move forward so as to compress the spring 5. The draft gear is now installed on the car and the 80 projections 15 and 19 having been forced toward each other by the action of the chisel, can be readily inserted within the space between the stops 16 and 20. The chisel is now removed and the projections 15 and 19 85 move back slightly until they engage the respective stops 16 and 20, which prevent further movement and thus hold the spring 90 under initial compression.

Under a buffing stress, the pressure is 100 transmitted through rod 11 to the front plunger wedge 8 and since the projections 19 engage the stops 20 and act as a follower plate, the movement of the plunger wedge 8 will force the wedge blocks 10 laterally 105 and rearwardly, so that the casing 3 is forced rearwardly, causing the compression of the draft spring 5.

When a draft stress is applied to the car, the yoke 1 is pulled forwardly and with it 110

the rear plunger wedge 9 and since the stops 16 prevent the forward movement of the follower extensions 15, the wedge blocks 10 will be forced laterally and forwardly, so that the friction element 6 is forced forwardly to compress the draft spring 5.

It will now be seen that the projections 15 and 19 take the place of the usual follower plates and since they are located at an intermediate point of the gear, the stops for same may be correspondingly located, thus permitting a reduction in the length of the stop castings, and dispensing with the space usually required for follower plates.

Having now described my invention, what I claim as new and desire to secure by Letters Patent, is:

1. The combination with a draw-bar, of a friction draft gear comprising front and rear friction elements each having oppositely inclined friction faces, centrally arranged plunger wedges having oppositely inclined friction faces, wedge blocks having friction faces adapted to coöperate with the friction faces of the friction elements and the plunger wedges, stationary stops, projections carried by said plunger wedges for engaging the stops, and a yielding resistance for opposing the movement of the friction members.

2. The combination with a draw-bar, of a friction draft gear comprising front and rear friction elements each having oppositely inclined friction faces, centrally arranged plunger wedges having oppositely inclined friction faces, wedge blocks having friction faces adapted to coöperate with the friction faces of the friction elements and the plunger wedges, stop castings secured to the car center sills and provided with stops,

projections carried by the plunger wedges for engaging said stops when the draw-bar is subjected to buffing and draft stresses, and a yielding resistance for opposing the movement of the friction members.

3. The combination with a friction draft gear comprising a casing having interior oppositely inclined friction faces, centrally arranged plunger wedges having oppositely inclined friction faces, a front friction element having oppositely inclined friction faces, a draft spring mounted between the casing and said friction element, wedge blocks having friction faces adapted to coöperate with the friction faces of the casing, said friction element, and the plunger wedges, stationary stops, and projections carried by the plunger wedges for engaging the stops.

4. The combination with a friction draft gear comprising, a casing having interior oppositely inclined friction faces, centrally arranged plunger wedges having oppositely inclined friction faces, a front friction element having oppositely inclined friction faces, a draft spring mounted between the casing and said friction element, wedge blocks having friction faces adapted to coöperate with the friction faces of the casing, said friction element, and the plunger wedges, projections carried by said plunger wedges, and stationary stops spaced to engage said projections and hold the draft spring under initial compression.

In testimony whereof I have hereunto set my hand.

EDWARD W. NEWELL.
